ILLUMINATED SIGN

Florence Samuel Ganoung, Clean, N. Y.

Application June 14, 1939, Serial No. 279,107

9 Claims. (Cl. 40—133)

My invention relates in general to electrically illuminated signs and more particularly to signs utilizing reflectors for varying the illumination of the sign.

It is highly desired in advertising through the use of a sign to convey a message clearly and quickly, to attract attention, and to present a pleasing appearance. The use of illumination aids in clearly presenting the characters of the sign for ready observation and the animation or change in illumination aids in attracting attention to the sign and in affording a pleasing and novel appearance.

It is an object of my invention to provide a sign having the above described desirable characteristics.

Another object is the provision of a sign having animated illumination of a distinctive and attractive character.

Another object is the provision of a sign for quickly catching the eye of the observer and for readily conveying the message displayed upon the sign.

Another object is the provision of a sign illuminated with different colored lights having varying effect upon the illuminated face of the sign.

Another object is the provision of a sign having spaced light sources of different character for emanating light of said different character upon the light transmitting face of the sign, the intensity of the light from each light source being varied by a reflector.

Another object is the provision of a sign having a light transmitting face and an illuminating arrangement for causing bands or waves of different colored lights move across the said face of the sign.

Another object is the provision of an arrangement for causing areas of distinctive color characteristics to be variously positioned upon the face of a sign.

Another object is the provision of an arrangement of light sources emanating light of different quality and reflecting means for varying the quality of light transmitted through portions of the illuminated portion of the sign.

Another object is the provision of a sign having translucent portions and transparent portions through which light is transmitted from the interior of the sign, illuminating means for transmitting light of different qualities through said transparent and translucent portions, and a reflector for recurrently changing the intensity of light of different qualities, respectively, trans-

mitted through local areas of the said translucent and transparent portion.

Another object is the provision of an illuminating arrangement for recurrently changing the character of light upon the face of the sign, the change of character of the light being decisive and pronounced in one portion of the face of the sign and being graduated and fused in another portion of the face of the sign.

Another object is the provision of an illuminated sign having recurrent changes in the quality of the light observed upon the face of the sign, there being a distinction between the changes in one portion of the face and the changes in another portion of the face.

A still further object is to provide an improved sign construction operating in a novel manner and producing a new and improved result.

And a still further object is the provision of a sign which is simple and efficient in operation, economical in construction and maintenance, and attractive in appearance.

A fuller understanding of my invention may be had by referring to the following description and claims taken in conjunction with the accompanying drawings, in which like parts are designated by like reference characters, and in which:

Figure 1 illustrates a sign embodying the features of my invention, as shown in a front elevation, with portions cut away to show the interior of the sign.

Figure 2 shows a cross-sectional view of the sign taken through the line 2—2 of Figure 1, showing principally the gaseous tubes.

Figure 3 shows a cross-sectional view of the sign taken through the line 3—3 of Figure 1, showing principally the gaseous tubes.

Figure 4 is a cross-sectional view taken through the line 4—4 of Figure 1.

Figure 5 is a cross-sectional view taken through the line 5—5 of Figure 1.

Figure 6 shows a portion of the glass plate upon the face of the sign in Figure 1 and illustrates one form of light transmitting face which may be used upon the sign.

Figure 7 is a section of another face which may be used for the sign and having a modified form.

Figure 8 is a cross-sectional view through the line 8—8 of Figure 6.

And Figure 9 is a cross-sectional view through the line 9—9 of Figure 7.

The particular form of sign illustrated in Figure 1 is of the type which may be extended over a side-walk from the side of a building. The

housing 10 is preferably made of sheet metal of generally rectangular outline with rounded ends, and includes an upper frame member 11 and a lower frame member 12 secured to the housing 10 by rivets or welding and extending longitudinally of the housing 10 adjacent to its upper and lower wall, respectively. The members 11 and 12 extend outwardly of the housing 10 upon the left hand end of Figure 1 and are adapted to be anchored to the side of a building. Within one of the arcuate ends of the housing there is mounted the vertical plate 13 welded or otherwise suitably secured to the members 11 and 12. At the other arcuate end of the housing 10, the members 11 and 12 are connected by the vertical angle member 14 and the vertical supporting member 15 welded thereto, respectively. A horizontal supporting member 16 is secured by bolts, welding, or other suitable means to the plate 13 and the vertical supporting member 15 at a position substantially half-way between the members 11 and 12. The members 11, 12, 13, 14, 15 and 16 are thus assembled and joined to provide a strong and rigid frame within the housing 10.

A plurality of cross-pieces 17 are mounted transversely of the members 11, 16, and 12 and are disposed in horizontal planes. The cross-pieces 17 in the upper portion of the housing 10 are secured to the upper wall of the housing 10 as well as to the member 11. The cross pieces 17 in the lower portion of the housing are secured to the lower wall of the housing as well as to the member 12. The cross-pieces 17 adjacent the member 16 are entirely supported by the member 16 as is illustrated in Figure 5. There are a plurality of spaced insulated supports 18 carried by the cross-pieces 17 and upon the insulated supports 18 are carried a plurality of gaseous tubes, the tubes being secured to the supports 18 in the usual manner. It is therefore seen from the several views that there are three banks of gaseous tubes positioned within the housing in spaced relationship in respect to the other banks of tubes.

A bracket support 27 secured to the members 11 and 12 supports a transformer 19 and a transformer 20 within one of the arcuate ends of the housing. The upper transformer 19 secured to the bracket 27 and the lower transformer 20 secured to the bracket 27 have suitable terminals connecting with the primary supply conductors 26 adapted to energize the transformers. The transformer 19 has the secondary leads 21 and 22 connected in circuit relationship with the gaseous tubes 28 of the upper bank of tubes and the gaseous tubes 29 of one-half of the intermediate bank of tubes. A suitable connection 23 connects the tubes 28 of the upper bank to the tubes 29 of the intermediate bank in circuit relationship. The transformer 20 has the secondary leads 24 and 25 connecting the tubes 31 of the lower bank of tubes and tubes 30 of one-half of the intermediate bank of tubes in circuit relationship. The lead 24 is connected to the beginning of tubes 31 and the lead 25 is connected to the end of the tubes 30. A suitable connecting cable 56 connects the end of the tubes 31 to the beginning of the tubes 30. By this arrangement two transformers are utilized for energizing the tubes arranged in three banks of tubes, each transformer contributing toward the energization of half of the intermediate bank of tubes. The arrangement of the lower tubes 31 is substantially the same as the upper tubes 28 and therefore a longitudinal cross-section view

through the bottom of the housing in the location of tubes 31 is not repeated. The type of quality of light emanating from the tubes is dependent upon the choice of the rare gases used in the tube, the character of the glass of the tube, the possible coating upon the tube, or in a combination of such variables. The tubes in any one bank may be of any one color or may be of a mixture to give a light of another desired quality.

10 The tubes in each bank may be thus selected to give any desired combination of colored light as may be desired. For example, the upper bank of tubes may emanate a light of red quality, the tubes of the lower bank may emanate a light of a 15 green quality and the tubes of the intermediate bank may emanate a light of bluish-white quality.

15 Elongated mirrors or reflecting members 35 and 36 are rotatively mounted within the housing 10 in such manner that the reflecting member 35 is intermediate the upper and the intermediate banks of tubes and the reflecting member 36 is intermediate the lower and intermediate banks of tubes. A shaft 32 extends along the reflecting member 35 and is secured thereto by the fastenings 37 in such a way as to cause the reflecting member 35 to revolve upon the rotation of the shaft 32. The shaft 33 is similarly secured to the reflecting member 36 in such a way as to cause the reflecting member 36 to revolve upon the rotation of the shaft 33. Suitable bearings 34 carried by the vertical member 15 and the plate 13 support the rods 32 and 33 in a manner to permit their free rotation.

20 There is a hole 38 and a hole 39 provided in the plate 13 for providing space for the driving arrangement for rotating the shafts 32 and 33. A sprocket wheel 40 is rigidly secured to the end of the shaft 32 so as to rotate therewith, the sprocket wheel 40 being positioned to be accommodated by the hole 38. The sprocket wheel 42 is similarly secured to the shaft 32 so as to rotate therewith. The endless chain 41 engaging the sprockets 40 and 42 causes the simultaneous rotation of 25 the shafts 32 and 33. The chain 41 passes through the holes 38 and 39 in the plate 13 so as to extend upon opposite sides of the plate 13. A sprocket wheel 43 is also rigidly secured to the shaft 33 adjacent to the sprocket wheel 42. The free end of the shaft 33 is rotatively carried by the bearing 44. The drive sprocket wheel 46 driven by the electric motor 47 is connected in driving arrangement with the sprocket wheel 43 by the chain 45. The electric motor 47 is mounted to the side of the vertical plate 13. Energization of the electric motor causes the drive wheel 46 to rotate the sprocket wheel 43 and shaft 33 and at the same time to rotate the shaft 32 through the chain 41. In the form of the driving arrangement illustrated in Figures 1 and 4 the reflecting members 35 and 36 are rotated in unison, in the same direction, and at the same angle relative to a plane passing through the shaft 32 and 33. Modifications may be made by 30 making certain changes in the driving arrangement described such as causing the reflecting members to rotate in opposite directions, at different angles to said plane, or in different synchronization. A reciprocating movement may also be obtained by certain changes in the driving arrangement in order to obtain a recurrent movement of the reflecting members by reciprocation rather than by rotation.

35 The reflecting members 35 and 36 may be formed of any material having the desirable re-

flecting characteristics, chrome plated metal being a preferable form of reflector. The reflecting member has substantially flat reflecting surfaces on opposite sides of the reflector and is relatively thin. The reflective surfaces disposed on opposite sides of the reflecting members with relatively little thickness between them afford a substantially continuous reflecting surface extending around both sides of the reflecting members. By this arrangement there is substantially at all times a reflecting surface disposed toward any one of the banks of light. As soon as one side of the reflecting member has turned away from deflecting position relative to a light source the opposite reflecting surface of the said reflecting member moves into reflecting position relative to said light source.

In the opposite flat rectangular sides of the housing 10 there are open spaces bounded by the peripheral edge portions 50. Rectangular frames 51 fit into the open spaces provided in the opposite side of the housing in a manner to engage in light proof engagement with the peripheral edge portions 50, respectively. A panel 52 of glass, plastic, or other suitable material is mounted within the open space in each frame 51 in a manner to close the open side of the housing and to thus provide an enclosure. By the arrangement shown different panels bearing different sign characters may be substituted in the sign. By merely removing the screws holding the frame 51 to the housing 10 the panel 52 and frame 51 may be quickly removed from the housing and another panel substituted. Likewise, the interior of the housing may be made accessible for inspection or replacement of tubes by the removal of a panel.

The panel 52 has light transmitting portions which are illuminated by the emanation of light from the tubes within the housing. The light transmitting panel portions are divided between a part that is transparent and another part that is merely translucent. Opaque portions may also be included in the panel 52 for the formation of the characters of the sign being displayed. Many different combinations of translucent material, transparent material and opaque material are possible in the construction of the panel 52. It is to be understood that in the meaning of the terms the transparent portion transmits light through the panel directly with substantially little diffusion and the translucent material transmits light through the panel 52 with a relatively large amount of diffusion.

For illustrative purposes some preferred methods of arranging the portions of the panel 52 are illustrated in Figures 6 and 7. By way of example, the letter "I" is shown as a character of the sign being displayed. The word "character" is to be considered in its broader meaning as covering not only letters but also symbols, ornamentations, and configurations. In the arrangement shown in Figure 6 the field or background is the opaque portion 53, the outline of the letter is the transparent portion 54, and the body of the letter is the translucent portion 55. A convenient method of forming the opaque portion 53, the transparent portion 54, and the translucent portions 55 is by the use of a panel of clear plate glass upon which opaque paint may be applied to form the opaque portions 53 and upon which a translucent paint may be applied or a frosting may be produced to obtain the translucent portions 55 leaving the transparent portions 54 clear.

In Figure 7 there is illustrated another ar-

rangement of portions of different character in the panel 52. In Figure 7 the opaque material 53 forms the body of the letter, the transparent portions 54 forms the outline of the letter, and the translucent portion 55 forms the background or field of the sign. Other arrangements for the panel 52 may include only a translucent portion and a transparent portion without the use of opaque material. Letters in relief may be applied to the plate 52 in one arrangement for obtaining the desired configuration. Also, in order to secure clear visibility of the sign in daylight when the interior of the sign is not illuminated the characters of the sign may be applied to the panel 52 so as to be visible without the need of the interior illumination of the sign.

Figures 8 and 9 are cross-sectional views through the lines 8-8 and 9-9 of Figures 6 and 7, respectively. These views illustrate the relative positioning of the portions of different character making up the panel 52.

The upper bank of tubes is adapted to emanate light of one quality, such as red, the bottom bank of tubes is adapted to emanate light of a second quality, such as green, and the middle bank of tubes is adapted to emanate light of a third quality, such as bluish-white. The light of each quality directly emanated from the respective banks of tubes upon the panel is most intense upon the local area of the panel adjacent to the respective banks of tubes. Under the examples given, the red light normally dominates the upper area of the panel, the green normally dominates the lower area of the panel, and the bluish-white light normally dominates the intermediate area of the panel. Light emanating to the panel from the respective banks to other areas beyond the local areas dominated is normally subdued by the dominant light of the adjacent banks of tubes.

The provision of the reflecting members rotating at the varying angles in respect to the banks of tubes and the panel disturbs the normal dominance of areas of the panel by the different quality lights. The reflected light is added to the light normally emanating to the panel to vary the intensity of the light of certain qualities appearing in areas of the panel. As a reflecting member progressively rotates the areas in which light of the different qualities dominates alternately expand and contract in response to the relative angularity of the reflecting member. This expansion and contraction of the areas dominated by different quality lights gives the appearance of waves or bands of light of different quality moving across the panel, up and down.

Under the example given, with the upper reflecting member in one position the red light will dominate most of the panel above the middle bank of tubes and the bluish-white area above the middle bank will be confined to a relatively small area. With the lower reflecting member at the same angle the bluish-white light will however dominate most of the panel below the middle bank and the green light on the bottom will be confined to a relatively small area. The dominance of the lights at the same time upon the opposite side of the sign will be of a reverse nature by reason of the opposite angularity of the effective reflective surfaces. Rotation of the reflecting members 90 degrees will reverse the pre-dominance of the colors and the extent of the areas dominated. Progressive rotation of the reflective member causes a shifting of the areas of predominance to animate the illumination of the panel with the constantly moving waves or bands of color.

By reason of the diffusion of light through the translucent portion of the panel the lights of different quality fuse along the margin between the areas dominated by different quality lights. The fusion of the red and bluish-white, for example, in the shift between the two colors gives the appearance of a graduated and slow change of waves or bands of color.

The direct transmittal of light through the transparent portion of the panel marks a more decisive and pronounced change. The waves or bands appear more distinct and separate to make the change over from one color to another seem to "flash." The comparison of the change appearing through the translucent portion and the change appearing through the transparent portion adds further animation and sparkle to the illumination of the sign. There is therefore not only the attraction to the sign obtained by the moving color waves or bands upon the panel generally but also the eye appealing feature of the comparison in changes appearing in the transparent and translucent portions of the panel.

Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. In an illuminated display device, a housing having an illuminated field opening, a panel positioned in the said opening to form a closed housing, said panel having a translucent portion and a transparent portion forming characters to be displayed, a first light source of one quality mounted within the housing adjacent one location of said panel for emanating light of said one quality to said panel, a second light source of another quality mounted within the housing adjacent a second location at a distance from said first location for emanating light of said another quality to said panel, said panel having a portion intermediate of said first and second locations to be illuminated, a light reflecting member having two reflective surfaces, said light reflecting member being movably mounted within the housing and between said first light source and said second light source, each said light source comprising a bank of gaseous tubes and lying substantially in parallel planes on opposite sides of the light reflecting member, the width of each bank of gaseous tubes being substantially the same width as the width of the light reflecting member and means carried by the housing for progressively moving said reflecting member to recurrently change its reflecting position relative to said first light source and to said second light source to alternately present each reflective surface toward the light sources and to recurrently illuminate said intermediate portion of the panel with alternately reflected light from said sources, the relative position of the first light source, the second light source and the reflecting member providing for the alternate reflection of light from said first and second light sources to said panel, the said alternate deflection changing the intensity of light transmitted to portions of the panel from said first light source and said second light source to vary the pre-dominance of light of different quality transmitted through the panel, the light transmitted through the transparent portion of the panel showing a clear

cut change of quality of lights in the said variation of pre-dominance, the light transmitted through the translucent portion of the panel showing a fusion of lights of different quality in the said variation of pre-dominance.

- 5 2. In an illuminated display device, a housing having an illuminated field opening, a panel positioned in the said opening to form a closed housing, said panel having a translucent portion and a transparent portion forming characters to be displayed, a first light source of one quality mounted within the housing in proximate lighting relationship to one local area of the panel for emanating light of said one quality to the 10 panel, a second light source of another quality mounted within the housing in proximate lighting relationship to another local area of the panel at a distance from the first light source and from said one local area of the panel for emanating light of said another quality to the 15 panel, the said lights of different quality being intensified on different of said local areas of said panel, a movable light reflecting member lying in a plane and having two reflective surfaces, said light reflecting member being mounted within the 20 housing and between the first and second light sources, each said light source comprising a bank of gaseous tubes and lying substantially in parallel planes on opposite sides of the light reflecting member, the width of each bank of 25 gaseous tubes being substantially the same width as the width of the light reflecting member, said light reflecting member being adapted to alternately reflect light from the first light source 30 and the second light source and from each of the two reflective surfaces to vary the areas of intensification of said lights of different quality on said panel intermediate of said local areas, the light transmitted through the transparent portion 35 of the panel showing a decided change of quality in the variation of said areas of intensification and the light transmitted through the translucent areas of the panel showing a fusion of the said different quality lights in the variation 40 of said areas of intensification.
- 45 3. An illuminated sign construction comprising, in combination, a housing having an illuminated field opening, a light transmitting material positioned in the field opening to form a closed 50 housing, said light transmitting material having a translucent portion and a transparent portion forming the characters of said sign, a plurality of spaced light sources mounted within the housing adjacent to different local areas of the light 55 transmitting material, said local areas being spaced to form an intermediate area in the plane of said material, said light sources being adapted to emanate light of different quality, said emanated light of different quality being intensified 60 at said different local areas relative to said intermediate area, respectively, of the light transmitting material, and movable light reflecting means having two oppositely disposed reflective surfaces, said light reflecting means being positioned 65 within the housing for alternately reflecting emanated light from different light sources from each of the two oppositely disposed reflective surfaces to said light transmitting material in varying degree of intensity on said intermediate area, said alternate deflection varying the said extent of the said areas of intensified light of different quality to animate the characters of said sign, each said light source comprising a bank of gaseous tubes and lying substantially 70 in parallel planes on opposite sides of 75

the light reflecting means, the width of each bank of gaseous tubes being substantially the same width as the width of the light reflecting means.

4. An illuminated sign construction comprising, in combination, a housing having a light transmitting wall on a side thereof, said light transmitting wall having transparent and translucent portions forming characters of the sign to be illuminated, a first light source of a first quality positioned within the housing adjacent a first local area of the light transmitting wall, a second light source of a second quality positioned within the housing adjacent a second local area of the light transmitting wall, a third light source of a third quality positioned within the housing adjacent a third local area of the light transmitting area, said local areas being spaced from each other in the plane of said wall and defining intermediate areas on said wall, said light sources being adapted to emanate light within the housing and through the light transmitting wall, plane light reflecting means having oppositely disposed reflecting surfaces rotatively mounted within the housing in the path of the light emanating from the said light sources for selectively and recurrently reflecting light from said light sources to said light transmitting wall to vary the intensification of quality of light transmitted through said intermediate areas of the light transmitting wall, the variance in intensification of light of different quality recurrently changing the quality of light transmitted through said transparent and said translucent portions of the light transmitting wall, said light reflecting means comprising two rotating reflecting members, one of said reflecting members being positioned between the first and second light sources and the other reflecting member being positioned between the second and third light sources, and means for actuating the rotating reflecting members.

5. An illuminated sign construction comprising, in combination, a housing having an illuminated field opening in a side thereof, a sheet of light transmitting material positioned in said opening to form a closed housing, a plurality of banks of gaseous tubes mounted substantially horizontally of said housing, one of said banks being positioned adjacent an upper portion of said sheet, a second of said banks being positioned adjacent a lower portion of said sheet, a third of said banks being positioned adjacent an intermediate portion of said sheet, each of said banks being adapted to emanate light of a different color characteristic within said housing and through said sheet, a first reflector rotatively mounted within the housing intermediate the first and third banks and a second reflector rotatively mounted within the housing intermediate the third and second banks, said reflectors having opposite reflective surfaces to afford substantially continuous reflection toward said sheet, and driving means for rotating said reflectors to vary their respective reflecting angle relative to said banks and said sheet, the rotation of the reflectors selectively deflecting light from said light sources to said sheet to recurrently vary the character of light transmitted through portions of said sheet.

6. An illuminated sign construction comprising, in combination, a housing, said housing having a side wall, said wall having a translucent and a transparent portion forming the sign to be illuminated, three banks of gaseous tubes

mounted in the housing in spaced relationship to each other and positioned adjacent to different local areas of said wall, each of said banks of tubes being adapted to emanate light of different color characteristic dominating said local areas, respectively, two reflectors having opposite reflective surfaces rotatively mounted in the housing intermediate said banks of tubes, driving means carried by the housing for rotating said reflectors to selectively and progressively reflect light from said banks of tubes, respectively, to said local areas of said wall, the said rotation changing the said dominance of color characteristic of the said local areas, the change of color characteristic of the translucent portion being graduated and the change of color characteristic of the transparent portion being decisive to provide distinction in the illumination of said portions.

7. The combination of two differently colored light sources spaced apart in a housing having two light transmitting walls, said two light sources being positioned adjacent to different local areas of each of said walls whereby light from each of said two sources falls on each of said walls, said local areas being separated by intermediate areas of said walls, respectively, a substantially flat reflector having oppositely disposed reflective surfaces rotatively mounted in the housing to alternately reflect light from said light sources at progressively varying angles to said light transmitting walls, and driving means carried by the housing for rotating said reflector, said alternate reflection at varying angles causing a progressive change in inverse ratio of the extent of the local and intermediate areas of the said wall through which the light from said light sources is intensified, each said light source comprising a bank of gaseous tubes and lying substantially in parallel planes on opposite sides of the light reflector member, the width of each bank of gaseous tubes being substantially the same width as the width of the light reflector member.

8. The combination of two differently colored light sources spaced apart in a housing having a light transmitting wall, said light sources being substantially equidistant from spaced portions of said wall, said light transmitting wall having a translucent portion and a transparent portion forming a character to be displayed, a substantially flat reflector positioned adjacent a portion of said wall intermediate of said spaced portions and movably mounted in said housing and adapted to receive light from said two sources and reflect it to said light transmitting wall, and means for recurrently moving said reflector to alternately reflect light from said light sources at progressively varying angles to said light transmitting wall, the said alternate reflection at varying angles causing a progressive change in the extent of the areas of the intensification of said lights of different color, respectively, dominating said spaced and intermediate portions of the wall, the change of said areas being pronounced at said transparent portion of the wall and being graduated at said translucent portion of the wall, each said light source comprising a bank of gaseous tubes and lying substantially in parallel planes on opposite sides of the light reflector member, the width of each bank of gaseous tubes being substantially the same width as the width of the light reflector member.

9. An illuminated sign construction comprising, in combination, a housing having a light

transmitting wall on a side thereof, said light transmitting wall having transparent and translucent portions forming characters of the sign to be illuminated, a first light source of a first quality positioned within the housing adjacent a first local area of the light transmitting wall, a second light source of a second quality positioned within the housing adjacent a second local area of the light transmitting wall at a distance from said first local area, a third light source of a third quality positioned within the housing adjacent a third local area of the light transmitting wall at a distance from said first and second local areas, said light sources being adapted to emanate light within the housing and through the light transmitting wall, said emanated light being relatively intense at said local areas and relatively weak intermediate of said local areas, plane light reflecting means having oppositely disposed reflecting surfaces rotatively mounted within the housing in the path of light

emanating from the said light sources for selectively and recurrently reflecting light from said light sources to said light transmitting wall to vary the extent of the intensification of light transmitted through said each of the local areas of the light transmitting wall toward a next adjacent local area, the variance in intensification of light of different quality recurrently changing the quality of light transmitted through said transparent and said translucent portions of the light transmitting wall, said light reflecting means comprising two rotating reflecting members, one of said reflecting members being positioned between the first and second light sources and the other reflecting member being positioned between the second and third light sources, and means for actuating the rotating reflecting members in synchrony with the reflecting members substantially parallel to each other.

F. SAMUEL GANOUNG.
